EXTENSIBLE RACK

Albert V. Elder, Portland, Oreg.

Application April 17, 1948, Serial No. 21,671

1 Claim. (Cl. 312—274)

1

This invention relates to an extensible rack adapted to be mounted in a closet space or drying compartment, or the like, in such a manner that it will be projected out into an accessible position when the door to the space or compartment is opened.

Objects of the invention are to provide an improved rack of neat appearance which will be extended from a kitchen cabinet or drying closet into an accessible position by opening the door to the cabinet or closet, to provide a rack of the type described having an extending mechanism operable in a small space, to provide improved mounting arrangements and linkages for extending the rack out of its closet space in rectilinear straight forward motion or substantially straight forward motion, and to provide a novel linkage for producing forward motion through a door opening by the angular movement of a hinged door.

The invention comprises in its preferred embodiments a plurality of parallel rack bars for supporting articles in a small cabinet or drying closet. In certain embodiments of the invention, the rack bars are mounted for forward sliding movement on horizontal supporting rails and in another embodiment of the invention the rack bars are carried by a parallelogram linkage to swing them forward out of the closet. In either case, the mounting arrangement is such as to eliminate or, at least, reduce sidewise motion of the rack bars when they are extended from the closet, so that a relatively narrow closet space may be efficiently used for drying or other purposes. The present invention enables the utilization of a narrow space which may be rather deep from front to rear and have ample capacity for various purposes but which would not be wide enough for the use of conventional racks and hangers. Various novel linkages are disclosed to extend the rack bars forwardly by the opening of a hinged door on the front of the closet.

Still further objects and advantages of the invention will become apparent as the description proceeds in connection with the accompanying drawings illustrating certain preferred embodiments. It is to be understood, however, that various changes may be made in the construction and arrangement of parts, and all such modifications within the scope of the appended claims are included in the invention.

In the drawings:

Figure 1 is a plan view of a sliding rack in retracted position with the closet door closed;

Figure 2 is a view of the rack shown in Figure 55

2

1 after it has been extended by the opening of the door and showing the linkage in two different adjusted positions;

Figure 3 is a perspective view of the door link shown in Figures 1 and 2;

Figure 4 is a perspective view of the rack link shown in Figures 1 and 2;

Figure 5 is a plan view of a modified form of sliding rack having a different linkage arrangement for extending the rack;

Figure 6 is a side elevation view of the rack shown in Figure 5;

Figure 7 is an enlarged plan view of a portion of the linkage shown in Figure 5 with the door in closed position;

Figure 8 is a view corresponding to Figure 7 showing the position of the parts when the door is partially opened; and

Figure 9 is a plan view of a modification in which the rack is mounted on a parallelogram linkage.

Referring first to Figures 1 and 2, the numeral 10 designates a side wall of a kitchen cabinet or drying closet and the like having a vertical door 11 mounted on hinges 12. The rear wall and the other side wall are not shown and it is understood that the closet may be provided with suitable heating and ventilating means. The present type of rack is particularly designed for a narrow space where there would be insufficient room for a swinging movement of the rack as it is being extended forwardly. The principal parts of the rack are carried by an angular supporting frame member 13 having a transverse rear portion 14 extending out at right angles from a longitudinal portion 15 which is adapted to form a base or bracket to be secured against the side of the wall 10. Extending forwardly from the rear portion 14 of the frame member are a pair of horizontal, parallel rails 16 to support a sliding rack member designated generally by the numeral 20. In the present embodiment the rails 16 comprise cylindrical members such as metal tubing which may be welded or otherwise secured to the frame member 13 to stand out horizontally therefrom, and the rack member 20 comprises a pair of parallel, tubular rack bar members 21 which are adapted to telescope over tubular rails 16 with a sliding fit. Two rails 16 are sufficient to support the rack member 20 and any number of additional rack bars 22 may be added by connecting them with a short transverse member 23 which is itself integrally connected with the rack bars 21. It is preferred to place the cross member 23 at a distance from the inner ends of the bars 21 so that

the latter may have added length to support the rack member in its fully extended position. With the illustrated linkage arrangement, it is necessary also to have some free space in the closet to the rear of cross member 23 for the movement of the linkage in extending and retracting the rack.

A vertical bearing is provided at 25 in the cross member 23 to receive a down-turned end 26 on the rack link 27 shown in Figure 4. The other end of this link has an up-turned end 28 received in a hole or bearing at 29 in one end of a lever 30. The other end of the lever 30 is pivotally mounted on a pin or bolt 31 in the frame member 13. The lever 30 is connected with the door 11 by the door link 32 shown in Figure 3. The rear end of this link has a down-turned end 33 formed on a laterally offset portion 34 for pivotal connection with the lever 30 at the point 35. The forward end of the link 32 has a laterally offset portion 36 to clear the hinge 12 and a down-turned end 37 to be pivotally engaged in one of a series of holes 38 in a bracket 39 secured to the door near its hinge edge.

When the end 37 is inserted in the second hole from the hinge end of the bracket 39, as shown in Figure 1, the rack will be fully extended when the door is opened back to place the parts in the positions shown in full lines in Figure 2. The laterally offset portion 36 is seen to clear the hinge 12 to allow the door 11 to swing through an angle of 180 degrees. By another adjustment of the door link 32 in a different hole, the rack can be fully extended by movement of the door to half opened position as shown in broken lines in Figure 2. This adjustment is desirable when the door is near a wall which will not permit it to be fully opened to its full line position and is accomplished by placing the end 37 in the fourth hole from the hinge end of the bracket 39 which, with the door in the half opened position, as shown, places the lever 30 and rack member 20 in substantially the same position shown in full lines. The other holes 38 provide further adjustment and enable the same bracket 39 to be used on both left and right hand doors without turning the bracket over. The rack is preferably designed so that it may be turned over for mounting on an opposite side wall when the door is hinged on the other side. For this purpose the end 26 of link 27 and pin 31 are insertable in their respective holes from the top side of the rack regardless of which side is uppermost.

With the link 32 in the second hole of the bracket, the extending motion of the rack member 20 is slow at the beginning of the opening of the door with the motion accelerating as the door is opened wider. With the link 32 in the fourth hole of the bracket as shown in broken lines, the extending motion of the rack member is faster in order to be completed in about a 90 degree movement of the door. The parts must, of course, be proportioned so that the end of the rack members will follow the movement of the door without running into the door before it is sufficiently open.

Figures 5 to 8, inclusive, illustrate a modification in which the major lever movement is in a vertical plane along the wall 10 so that the mechanism will not limit the available space in a narrow cabinet. This modification is especially for use where extreme extension of the rack is desired in spaces where opening of the door is limited or where the extreme narrowness

of the space to be used necessitates the placing of the rack bars very close to the side of the space. In this embodiment the frame member 40 has a vertical portion 41 and a lower horizontal portion 42 lying flat against the surface of wall 10 and adapted to be mounted thereon by screws or the like. This frame also has an upper horizontal portion 43 extending out from the wall to carry the parallel, tubular rails 16 which slidably support the rack member 45.

The rack 45 comprises a pair of tubular rack bars 46 telescopically mounted on the tubular rails 16 and interconnected by a transverse member 47. The member 47 has one end extending toward the wall 10 and provided with a hole at 48 forming a bearing for an end 49 of rack link 50. The other end of the link 50 has an end 51 extending through a hole or bearing at 52 in the upper end of a lever 53 whose lower end is pivotally mounted at 54 on the lower horizontal portion 42 of the frame member 40. The lever 53 has a hole or bearing at 55 to pivotally receive the end 56 of a long door link 57. The forward end of the link 57 has an end 58 pivotally mounted in a hole or bearing 59 in one arm of a bell crank lever 60 which is pivotally mounted at 61 on a bracket 62 secured to the wall 10. The other arm of the bell crank lever has a hole or bearing 63 receiving the end 64 of a short door link 65 having an opposite end 66 pivotally mounted in a hole or bearing 67 in a bracket 68 on the door 11.

This form of construction shown in Figures 5 to 8 has the advantage of confining the movements of the link 50 and lever 53 in vertical planes close to the wall 10 so that these parts will not interfere with the use of the rack. The mechanical advantage of the linkage is such that the link 57 and bell crank lever 60 are not swung far out from the wall 10. Also, it will be observed from Figures 7 and 8 that the action on the rack is very slow as the door starts to open, substantially no movement of the rack occurring until after the door is opened in the clear beyond the position shown in Figure 8. As the door is opened further, the speed of the action rapidly increases to extend the rack to its outermost position without substantially more than 90° movement of the door. This type of action permits the use of long rack bars positioned close to the inner face of the door when the latter is closed and also relatively close to the hinged edge of the door.

Figure 9 illustrates an embodiment in which the rack member is supported on a parallelogram linkage. In this embodiment the wall bracket 70 is in the form of a channel having a web portion attached to the wall and upper and lower flanges standing out horizontally from the wall and apertured to provide pivotal mounting for a pair of vertical bolts 71. A pair of lever arms 72 are integrally connected with the upper ends of the bolts 71 to maintain the arms in horizontal positions throughout their pivotal movements. The outer ends of the arms 72 are pivotally connected at 73 to a pair of cross members 74 and 75 supporting a rack member 76 comprising a plurality of tubular rack bars 77. The two arms 72 are of the same length, and the spacing of the pivots 73 is the same as the spacing of the bolts 71 to provide a parallelogram linkage wherein the rack bars 77 will always be parallel with the wall 10. An additional pair of arms 75 may be secured to the lower ends of bolts 71 to

extend under the rack 76 directly beneath the arms 72 to provide a stronger support if desired.

A door link 78 has an inner end pivotally connected with one of the levers 72 at 79 and an outer offset end 80 inserted in one of a series of holes 81 for pivotal action in a bracket 82 on the door 11 similar to the arrangement shown in Figures 1 and 2. The end 80 is set in a selected hole 81 to impart the desired movement to the rack assembly and to allow the link 78 to clear the door and the wall when the door is opened to fully extend the rack. In this embodiment, the rack assembly moves laterally in parallel motion away from the wall 10, as it is extended, and so the cabinet space must be wide enough to provide clearance for this movement. The parallel motion of this linkage requires less lateral clearance, however, than conventional swinging racks.

The present forms of rack facilitate the utilization of a deep, narrow space which would otherwise be practically inaccessible and useless.

Having now described my invention and in what manner the same may be used, what I claim as new and desire to protect by Letters Patent is:

An extensible rack mechanism for a closet or the like having a side wall and a door vertically hinged at the front end of said side wall, comprising a frame having a horizontal member ex-

tending along one side of the rack and adapted for mounting on said side wall to furnish the sole support of the rack, a rack member having a plurality of parallel horizontal bars mounted on said frame for longitudinal parallel movement relative to said frame member, a lever pivotally mounted on said frame member and pivotally connected with said rack member, and a link connected with said lever and disposed along 5 said one side of the rack for connection with said door to extend said rack member out of the closet when the door is opened.

ALBERT V. ELDER.
